UNITED STATES PATENT OFFICE.

GUSTAV KELLER, OF EISENACH, GERMANY.

ADJUSTABLE STRUT WITH TOGGLE ACTION.

No. 856,159.

Specification of Letters Patent.

Patented June 4, 1907.

Application filed December 22, 1906. Serial No. 349,150.

To all whom it may concern:

Be it known that I, GUSTAV KELLER, manager, a subject of the Duke of Saxe-Meiningen, residing at Eisenach, Grand Duchy of Saxe-Weimar-Eisenach, German Empire, have invented certain new and useful improvements in or relating to adjustable struts with toggle action suitable for use in all deep level excavations, more particularly for pits, shafts, and wells, of which the following is a specification.

My invention relates to improvements in or relating to adjustable struts with toggle action suitable for use in all deep level excavations, more particularly for pits, shafts and wells.

Supports with toggle action are already well known in mining. It is also no longer new to use spreading levers with toggle action for joining separate rail sections on portable railways. These well known stay and spreading lever devices, however, are not adjustable to the extent absolutely necessary for struts for all deep-level excavations, more particularly for pits, shafts and wells, the so-called "canal struts."

The object of the present invention is to produce a canal strut which is adjustable within as wide limits as possible, which can be extended to any desired extent by securing several strut-bars together, and can be placed with one push into the spread-out position, and just as quickly, and without any danger, again detached after the securing device has been shifted.

"Canal struts" as heretofore known, do not have the above mentioned advantages, as they are adjustable merely by means of a spindle with a right and left-hand screw thread. "Canal struts" of such construction cannot be secured or detached again from the top by means of a suitable tool. This is, however, rendered possible by the canal strut according to the present invention; it is, therefore, unnecessary, as with the known struts with screw action, to have a firm stand when it is desired to put the strut in, which is an important advantage, for in most cases it is impossible to get such a stand, more particularly in canal building. But if there be no secure stand when well known screw struts are put in, then the putting in and the detaching of the struts is exceedingly dangerous for the workmen.

The new and distinguishing feature of the canal strut according to this invention is that

it is constituted by two or more bars of any desired cross section hinged together in a detachable manner by means of pins or the like, and in such way that their length is adjustable within the widest possible limits, the strut bars being secured in the operative position by means of an adjustable collar or ring; the adjustment of the length is effected by means of holes arranged at certain intervals.

Several constructions of "canal struts" according to the present invention are illustrated by way of example, in the accompanying drawings.

One construction is shown in Figure 1 in elevation, the strut being shown placed between the canal boards without being tightened. Fig. 2 shows the strut in elevation, in stretched position. Fig. 3 is a corresponding plan, and Fig. 4 a cross-section on the line A—B. Fig. 5 is a perspective view of a canal strut with the bars arranged to form a short length, for use when the canal boards are at a small distance from each other. While in the construction shown in Figs. 1 to 5 the struts are made of two U-shaped bars, the construction shown in Fig. 6 intended for smaller canals and easily constructed, comprises a T-shaped bar and two angle irons with their wider webs secured together by means of a flat iron bar placed between them. Figs. 7 and 8 show two other constructions of canal struts made of U-iron. Fig. 9 is a detail of the canal strut shown in Fig. 8. Fig. 10 is a section on the line C—D through the canal strut shown in Fig. 11, and constituted by a square beam and a U-iron. The strut shown in Fig. 12 is constituted by a round wooden beam and a U-iron. Fig. 13 is a detail, while Figs. 14 to 18 are sections on the line E—F of different constructional forms of the strut shown in Fig. 12.

The strut bars 1 and 2 at their ends adjacent to the canal boards 3 and 4 are provided either direct with claws 5^a or with shoes 5 having such claws. The bars 1 and 2 are preferably of unequal length, and the longer one is provided with a series of holes 6, while the shorter one has two holes 7 and 12 and 13, the distance between the holes 7 being half as long as the distance between the holes 6.

When inserting the canal strut, the two bars 1 and 2 are connected together by means of a pin positioned to give them the proper

length and placed between the canal boards 3 and 4 (Figs. 1 and 5). Thereupon the canal strut is forced into the stretched position (Fig. 2), and the safety ring or collar 9, mounted on the bar 1, is pushed over the bar 2 (Figs. 2 and 3). In this way the canal strut is forced to keep the position given to it, until the ring 9 is again withdrawn. By raising or pulling upward the bars 1 and 2 by means of a cable or chain attached near the pin 8, the canal strut can be brought into the position shown in Figs. 1 and 5, from the canal top that is to say from outside the canal itself, and thus removed in a very convenient way and without any danger.

Fig. 5 clearly shows that when U-irons are used, one bar 1 is cut out at the hinge end, so that the central web is removed. Owing to the shorter bar 1 being provided with two holes 7, the strut can be more easily lengthened and shortened within narrow limits than if the bar 1 were provided with only one hole 7.

In the event of the canal strut being still insufficiently long when the boards 3 and 4 to be stayed are at a great distance apart, several bars 1 and 2 can be connected together into one single strut by means of pins 8 as shown in Fig. 7.

The two outer strut bars 1^a and 2^b could also be utilized as canal boards, while the bars 1 and 2^a and 2 and 1^b form a rigid strut, being connected by means of the pin 8, and the ring 9 pushed over them. In this way any desired number of bars 1 and 2 can be connected to form one single strut, and thus, as the single bars 1 and 2 can be adjusted relatively to each other, the strut can be adjusted to suit any desired width of canal.

In the construction of the canal strut made of two U-irons 1 and 2, as shown in Fig. 8, in order to secure the strut in the stretched position without the use of a ring 9, the pivoted end of the U-iron is slightly bent upward and provided with a stop pin 14, so that the strut cannot sink downward beyond the stretched position after the stop pin 14 has come to rest against the bar 2.

In order to make the strut adhere properly to the canal boards, the free ends of the bars 1 and 2 may be provided, as shown clearly in Fig. 9, with detachable shoes 15 fitting each end of the bar, made of angle iron, secured by means of bent lugs 16 by screws or the like, and provided with points 17.

In the construction shown in Figs. 11 and 12, one of the bars is constituted by a wooden beam of square or round cross-section, while the second bar 2 is constituted by a U-iron. The beams 1 are preferably provided with a head piece 18 made of U-iron, as shown in Fig. 13, of which the upwardly bent flap 19 rests against the head of the beam and thus receives the pressure of the stretched strut.

The head piece 18 is secured to the wooden

beam by bolts 23 and pivoted to the U-iron 2 by means of a pin 8. To that end, the head piece 18 is provided with several holes 7 arranged close together, enabling the strut to be lengthened and shortened within narrow limits.

When square beams are used as shown in Fig. 11, the U-iron 2 preferably overlaps the head piece 18 as shown in the cross section in Fig. 10. A cranked head piece (Fig. 17) with the U-bar 2 arranged inside may equally well be employed. When round wooden beams are used, as shown in Fig. 12, the U-iron 2 is preferably arranged between the side webs of the head piece 18 as shown in Figs. 80 to 18 which represent various constructions shown in cross section on the line E—F.

In the construction shown in Fig. 14, the head piece is constituted by a pipe of which one end 20 is pushed over the round beam 1 and secured by means of bolts 23, while the other end is slit longitudinally. The lugs 21 thus produced, are bent upward and pivoted by pins 8 to the U-iron 2.

The spread-out position of these canal struts may be secured by pushing the ring 9 over the two bars, or by means of a second bolt introduced into the holes 7. In order to prevent the rings from getting lost, the bars may be provided at suitable points with stops which in the case of U-irons, have the shape of projections, rivet heads or the like.

In the constructions shown in cross section in Figs. 15 to 18, the shape of the head piece 18 is practically the same as in Fig. 13. In Fig. 15, in order to afford a firm support to the U-iron 2 in stretched position, two flat iron strips 22 are arranged at both sides of the beam 1. In Fig. 16 the U-iron bar 2 is replaced by a bar 25 of arc-shaped cross section. The firm support for the U-iron 2 in stretched position of the strut can also be obtained, as shown in Fig. 17 by bending the two side lugs of the U-iron 18 at 24, so that the U-iron 2 can rest on the bent portions. Fig. 18 shows a very simple construction, in which the U-iron 2 simply rests on the round wooden beam 1. In the constructions shown in Figs. 10 to 18, the bar 2 in stretched position always comes to rest on the bar 1.

What I claim is:

1. An adjustable strut with toggle action, comprising two oppositely facing yoke formed interfitting bars detachably pivoted together, one of said bars having a series of perforations, and the other having two series of perforations, the distance between the perforations comprising one of the series of the latter bar being one-half as long as the distance between the perforations in the former bar, and means for securing the bars together.

2. An adjustable strut with toggle action, comprising two oppositely facing yoke formed interfitting bars detachably pivoted

together, one of said bars having a series of perforations, and the other having two series of perforations, the perforations of one of the latter series being adapted to register with the series of perforations in the first mentioned bar, and means for securing the bars together.

3. An adjustable strut with toggle action, comprising two oppositely facing yoke formed interfitting bars, one of said bars having a series of perforations, and the other having two series of perforations, each of which is located adjacent the terminals of the bar, the perforations of one of the latter series being adapted to register with the series of perforations in the first mentioned bar, and means for securing the bars together.

4. An adjustable strut with toggle action, comprising two oppositely facing yoke formed interfitting bars detachably pivoted together, each of said bars being provided with means whereby a plurality of bars may be connected thereto to form a single rigid bar.

5. An adjustable strut with toggle action, comprising two oppositely facing yoke formed interfitting bars detachably pivoted together, each of said bars being provided with means whereby a plurality of bars may be connected thereto to form a single rigid bar, one of said bars having a series of perforations, the other having two series of perforations, the distance between the perforations comprising one of the series of the latter bar being one-half as long as the distance between the perforations in the former bar.

6. An adjustable strut with toggle action, comprising two oppositely facing yoke formed interfitting bars detachably pivoted together, each of said bars being provided with means whereby a plurality of bars may be connected thereto to form a single rigid bar, one of said bars having a series of perforations and the other having two series of perforations, the perforations of one of the latter series being adapted to register with the series of perforations in the first mentioned bar.

7. An adjustable strut with toggle action, comprising two oppositely facing yoke formed interfitting bars detachably pivoted together, each of said bars being provided with means whereby a plurality of bars may be connected thereto to form a single rigid bar, one of said bars having a series of perforations and the other having two series of perforations, each of which is located adjacent the terminals of the bar, the perfora-

tions of the latter series being adapted to 60 register with the series of perforations in the first mentioned bar.

8. An adjustable strut with toggle action, comprising two bars detachably pivoted together, the pivoted end of one of the bars being bent upwardly, and provided with a stop pin against which the other bar is adapted to engage, one of said bars having a series of perforations and the other having two series of perforations, the distance between the 70 perforations comprising one of the series of the latter bar being one-half as long as the distance between the perforations in the former bar, each of said bars being provided with means whereby a plurality of bars may be 75 connected thereto to form a single rigid bar.

9. An adjustable strut with toggle action, comprising two bars detachably pivoted together, the pivoted end of one bar being bent upwardly and provided with a stop pin 80 against which the other bar is adapted to engage, one of said bars having a series of perforations and the other having two series of perforations, the perforations of one of the latter series being adapted to register with 85 the series of perforations in the first mentioned bar, each of said bars being provided with means whereby a plurality of bars may be connected thereto to form a single rigid bar.

10. An adjustable strut with toggle action, comprising two bars detachably pivoted together, the pivoted end of one bar being bent upwardly and provided with a stop pin against which the other bar is adapted to engage, one of said bars having a series of perforations and the other having two series of perforations, each of which is located adjacent the terminal of the bar, the perforations of one of the latter series being adapted to 90 register with the series of perforations in the first mentioned bar, each of said bars being provided with means whereby a plurality of bars may be connected thereto to form a single rigid bar.

11. An adjustable strut with toggle action, comprising two oppositely facing yoke formed interfitting bars detachably pivoted together, and means for securing the bars in their adjusted position.

In testimony whereof I have hereunto set my hand in presence of two subscribing witnesses.

GUSTAV KELLER.
